UNITED STATES PATENT OFFICE.

DAVID S. HAWKINS, OF LAKEWOOD, OHIO, ASSIGNOR OF ONE-HALF TO A. W. MARGILETH, OF CLEVELAND, OHIO.

DESIGN FOR A CARD-BACK OR SIMILAR ARTICLE.

41,657.

Specification for Design.

Patented Aug. 8, 1911.

Application filed September 8, 1908. Serial No. 452,160. Term of patent 14 years.

To all whom it may concern:

Be it known that I, DAVID S. HAWKINS, a citizen of the United States, residing at Lakewood, in the county of Cuyahoga and State of Ohio, have invented a new, original, and ornamental Design for Card-Backs or Similar Articles, of which the following is a specification, reference being had to the accompanying drawing, forming a part hereof.

The figure represents a plan of a card back or similar article to which my design is applied.

I claim:

The ornamental design for a card back or similar article as shown.

DAVID S. HAWKINS.

Witnesses:

S. E. FOUTS,

BRENNAN B. WEST.
